(57) **CLAIM**

The ornamental design for an inflator and flat tire repair machine, as shown and described.

DESCRIPTION

The patent or application file contains a least one drawing executed in color. Copies of this patent or patent application publication with color drawing(s) will be provided by the Office upon request and payment of the necessary fee.

FIG. 1 is a perspective view of a inflator and flat tire repair machine showing my new design;

FIG. 2 is a right side elevation view thereof;

FIG. 3 is a left side elevation view thereof; and,

FIG. 4 is a top plan view thereof;

Bottom view portions of the machine and any other portions not shown form no part of the claimed design.

1 Claim, 4 Drawing Sheets
